DESIGN FOR A TIMEPIECE DIAL

Charles Stern, Geneva, Switzerland

Application September 7, 1945, Serial No. 121,917

Term of patent 7 years

(CL. D42—10)

To all whom it may concern:

Be it known that I, Charles Stern, a citizen of Switzerland, residing at Geneva, Switzerland, 3, Sentier des Saules, have invented a new, original, and ornamental Design for a Timepiece Dial, of which the following is a specification, reference being had to the accompanying drawing, forming part thereof.

In the drawing:

Fig. 1 is a plan view of a time-piece dial showing my new design;

Fig. 2 is a fragmentary perspective view; and

Figs. 3 and 4 are respectively, a fragmentary side elevational view and a fragmentary top plan view thereof.

I claim:

The ornamental design for a timepiece dial, substantially as shown.

CHARLES STERN.
